US00D599492S

(12) United States Design Patent
Wang et al.

(10) Patent No.: US D599,492 S
(45) Date of Patent:  Sep. 1, 2009

(54) FLASHLIGHT

(75) Inventors: Chun-Yuan Wang, Taipei (TW);
Hsiao-Cheng Chen, Taipei (TW);
Cheng-Yi Lee, Taipei (TW)

(73) Assignee: Pegatron Corporation, Taipei (TW)

() Term: 14 Years

(21) Appl. No.: 29/330,396

(22) Filed: Jan. 6, 2009

(30) Foreign Application Priority Data

Nov. 17, 2008 (TW) 97306573

(51) LOC (9) Cl. 26-02

(52) U.S. Cl. D26/49

(58) Field of Classification Search D26/37,
D26/46, 49; 362/157, 158, 183, 187, 188,
362/190, 191, 197, 201, 208, 103-108

See application file for complete search history.
